UNITED STATES PATENT OFFICE.

FRED E. BRADFIELD, OF DAVENPORT, IOWA.

DESIGN FOR A HOOD FOR AUTOMOBILES.

54,372.

Specification for Design.

Patented Feb. 10, 1920.

Application filed October 20, 1919. Serial No. 332,112. Term of patent 7 years.

To all whom it may concern:

Be it known that I, FRED E. BRADFIELD, a citizen of the United States, residing at Davenport, in the county of Scott and State of Iowa, have invented a new, original, and ornamental Design for Hoods for Automobiles, of which the following is a specification, reference being had to the accompanying drawings, forming part thereof.

In the drawings,—

Figure 1 is a perspective view from the front of an automobile hood showing my

new design, the radiator and a portion of the body of an automobile being shown in dotted lines in connection with the hood.

Fig. 2 is a perspective view from a point at one side and slightly above the parts shown in Fig. 1.

Fig. 3 is a top view of the same parts.

I claim:

The ornamental design for a hood for automobiles as shown.

FRED E. BRADFIELD.
